UNITED STATES PATENT OFFICE.

HENRY E. BRYANT, OF ATLANTA, GEORGIA.

COMBINED ERASER AND PENCIL-SHARPENER.

970,984.

Specification of Letters Patent. Patented Sept. 20, 1910.

Application filed November 18, 1909. Serial No. 528,737.

To all whom it may concern:

Be it known that I, HENRY E. BRYANT, a citizen of the United States, residing at Atlanta, in the county of Fulton and State of Georgia, have invented new and useful Improvements in Combined Erasers and Pencil-Sharpeners, of which the following is a specification.

This invention relates to a combined eraser and pencil sharpener, the object in view being to provide a simple, cheap and effective device of this character comprising a body of erasing material, a sharpening blade carried thereby, and a guard for covering the blade when not in use to prevent injury to the hand of the person using the eraser.

The invention consists of the features of construction, combination and arrangement of parts hereinafter fully described and claimed, reference being had to the accompanying drawing, in which:

Figure 1 is a top plan view of the device with the guard closed. Fig. 2 is a similar view with the guard open. Fig. 3 is a transverse section. Fig. 4 is a section taken at right angles to Fig. 3.

Referring to the drawing, 1 designates the body of the device, which preferably comprises a circular disk of erasing material, such as rubber or rubber combined with an abrading surface, as desired. Extending through and between the sides of said disk is a diagonally inclined slot 2 which is aligned with slots 3 and 4 in metallic reinforcing plates 5 and 6 bearing against the respective sides of the disk, which plates are preferably of circular form and less diameter than the disk, as shown. These plates are fastened at diametrically opposite sides to the disk by rivets 7 and 8 which pass transversely through said disk. The headed end of the rivet 7 which passes through the plate 5 is countersunk in a depression or recess 9 formed in the plate adjacent one end of the slot 3, as shown.

A blade 10 is arranged in the slot 2 and may be fixed to the disk and plates or otherwise supported in position. This blade has a beveled cutting edge 11 extending through the slot 3 in the plate 5 and projecting sufficiently to form a planing cutter, so that by alternately reciprocating and rotating the end of a pencil across the plate, the wood casing of the pencil may be cut away and

the point sharpened. The operation of sharpening the pencil may also be performed by the operator drawing the pencil toward him, or by shoving it away from him, as preferred. The slot is of greater width than the thickness of the blade to provide a discharge passage for the chips.

The disk may be employed in an obvious manner so that its periphery may be used as a pencil or an ink eraser according to the material of which the disk is made. In such use, the edge of the blade should be covered in order to prevent injury to the thumb or fingers of the operator. For this purpose a circular guard plate or cover 12 is employed which is coextensive in diameter with the plate 5 so that it may completely overlie the slot 3 and edge 11. This guard plate has at one side a boss 13 which pivotally engages the projecting end of the rivet 8, and at its diametrically opposite side is indented to form a spring stud 14 to engage the keeper 9, whereby the plate may be secured in guarding position against casual displacement. The guard is preferably corrugated or serrated in order that it may be readily swung on its pivot to open and closed positions. When sufficient force is applied to open the guard, the stud 14 will ride out of the keeper, as will be readily understood. An eye 15 is provided upon the plate 6 for the attachment of a cord in order to enable the device to be secured against loss or displacement.

In providing a combination article of this character great convenience is afforded to clerks, stenographers and others, and the construction is such as to enable the device to be economically made.

I claim:

1. A device of the character described comprising a body of erasing material having a slot therein, reinforcing plates disposed on opposite sides of the body and having registering slots, a blade disposed in the slot in the body and having a cutting edge projecting through the slot in one of said plates, the latter plate being provided with a locking depression or recess, rivets extending through the body and plates and uniting the same, and a guard pivotally mounted upon one of said rivets, said guard having a locking indentation to engage said locking recess.

2. A device of the character described comprising a body of erasing material hav-

ing a slot therein, reinforcing plates secured to opposite sides of the body and having registering slots, a blade disposed in the slot in the body and having a cutting edge projecting through the slot in one of said plates, and a pivoted guard for covering the edge of the blade.

In testimony whereof I affix my signature in presence of two witnesses.

HENRY E. BRYANT.
